UNITED STATES PATENT OFFICE.

ELLA L. SMITH, OF ROANOKE, ALABAMA.

MOLD FOR AND METHOD OF DOLL CONSTRUCTION.

Application filed August 2, 1922. Serial No. 579,103.

To all whom it may concern:

Be it known that I, ELLA L. SMITH, a citizen of the United States of America, residing at Roanoke, in the county of Randolph and State of Alabama, have invented certain new and useful Improvements in Molds for and Methods of Doll Construction, of which the following is a specification.

10 My invention relates to improvements in mold for and method of doll construction, and comprises the steps in the method of making the improvement.

An object of my invention is to provide 15 a method of manufacturing indestructible dolls.

A further object of my invention is the construction of an indestructible doll by an economical and rapid method which may be 20 carried out by persons relatively unskilled in the molding and in the construction of toys.

25 A further object of my invention is to construct a two-piece doll head forming all the parts of the face and the head in a single operation from a four-piece mold; that is, one operation in forming the front of the head and the side of the head and ears, and another in forming the back of the 30 head.

With these and other objects in view, one embodiment of my invention is illustrated in the accompanying drawings in which:—

Figure 1 is a plan view of the inner side 35 of the front head and the side of the head and ear molds;

Figure 2 is a plan view of the inner side of the back of the head mold;

Figure 3 is a section on line 3—3 of Figure 1;

Figure 4 is a section on line 4—4 of Figure 2;

Figure 5 is a side elevation of the inner side of one of the sides of the head and ear 45 molds;

Figure 6 is a section on line 6—6 of Figure 1;

Figure 7 is a side elevation of a complete 50 doll head, joined together with stitches;

Figure 8 is a side elevation of a complete doll head joined together with staples; and

Figure 9 is a section on line 9—9 of Figure 8.

In the construction of my improved doll head I use a four-piece mold. The front of the head mold 1 contains the usual recesses

for forming the front part of the face. There are two of the side of the head and ear molds 2 and 3 which are duplicates. The back of the head mold 4 consists of a single piece. The front of the head and the back of the head molds may consist on the outside of babbitt or similar metal parts 5 and 6, joined to lighter parts 7 and 8, respectively, made of plastic or other lighter material. The front of the head and the back of the head molds may consist of one piece of metal or other suitable material instead of two pieces. The side of the head and ear molds are made of babbitt or other suitable metal. In order to hold the side of the head and ear mold parts in proper position relative to the front of the head mold during the molding operation, two points 9 are molded on each of the molds 75 which fit into sockets 10 made in the front of the head mold.

The process of making a complete doll head as shown in Figures 7 and 8 comprises placing a layer of fabric 11 such as stockinette or other elastic material in each of the molds as shown in Figures 1 and 2. On this fabric layer is placed a plastic layer 12 which is then covered by fabric layer 13 which is covered by plastic layer 14. The ends 15 of the fabric layer 11 are turned over a short distance on the plastic layer 14. After the material has hardened, the parts of the head are removed from the molds, the mold parts 2 and 3 being lifted off of part 90 1. It will be noted that the ear 16 has been formed in the same manner as the nose and mouth in the recess 16^a in molds 2 and 3. The two parts of the head may be stitched together as indicated at 17, or may be stapled together as indicated by staples 18. After the two parts have been secured together, the opening between the two parts may be filled with cotton 19 or other suitable material. It will be apparent that a 100 doll head constructed in the manner indicated will be practically indestructible, the layers of fabric preventing the plastic part from getting out of place and the filling preventing the plastic on the inside from 105 changing its position even if broken.

The method of forming doll heads may, of course, be applied to the construction of the trunk or other parts of a doll, as well as to the construction of animals of the 110 kind usually referred to under the head of toys.

The head of the doll may be suitably painted to produce distinctive features by well-known methods, and as described in my Patent No. 1,321,135 of November 11, 5 1919.

It is evident that instead of using fabric in forming the doll head, I may use any other suitable material, such as soft leather.

It is obvious that the seam or line made 10 by joining the front and back pieces of the head may be covered by paint used in finishing the doll head or it may be covered by gluing over it a narrow strip of textile or other suitable material and then painting 15 over the strip.

Having described my invention, what I claim and desire to protect by Letters Patent is:—

1. A mold for the manufacture of dolls 20 comprising four parts, one of said parts adapted to mold the front of the head, one the back of the head, and two the side of the head and ears.

2. A mold for the manufacture of dolls 25 comprising four parts, three of said parts adapted to mold the front of the head and side of the head as one piece and the other part adapted to mold the back of the head.

3. A mold for forming the head of a 30 doll, said mold comprising duplicate parts

adapted to mold the ears as a part of the front of the doll head.

4. A mold for manufacturing doll heads comprising front and back pieces and two 35 duplicate intermediate pieces, said intermediate pieces having locking points thereon fitting into sockets in the face of the front piece.

5. The method of constructing doll heads 40 which comprises forming two parts thereof by placing an initial layer of fabric in a three-part mold and in a one piece mold, covering these layers with a layer of plastic, then applying successive layers of fabric 45 and plastic, allowing the plastic material to set, joining together the two parts and stuffing the opening between the parts with resilient material.

6. The method of constructing doll heads 50 which comprises forming two parts thereof in a four-piece mold, forming the front part thereof in three pieces of said mold, said part consisting of the front of the head and the middle part of the head including the ears, forming the back of the head in the remaining piece of said mold, and attaching the parts together.

In testimony whereof I affix my signature.

ELLA L. SMITH.
